UNITED STATES PATENT OFFICE

113,611

DESIGN FOR A FISH LURE

Joseph McArthur, Dowagiac, Mich., assignor to James Heddon's Sons, Dowagiac, Mich., a corporation of Michigan

Application August 1, 1938, Serial No. 79,007

Term of patent 14 years

To all whom it may concern:

Be it known that I, Joseph McArthur, a citizen of the United States, residing at Dowagiac, in the county of Cass and State of Michigan, have invented a new, original, and ornamental Design for a Fish Lure, of which the following is a specification, reference being had to the accompanying drawing, forming part thereof, wherein is illustrated in Fig. 1 a side elevation and in Fig. 2 an end elevation of a fish lure, showing my new design.

I claim:

The ornamental design for a fish lure, as shown.

JOSEPH McARTHUR.
